FIG. 3.

INVENTOR:

Thomas Barbour

by Monroe Miller Atty.

UNITED STATES PATENT OFFICE.

THOMAS BARBOUR, OF BELFAST, IRELAND.

HACKLING MACHINE.

Application filed June 3, 1926, Serial No. 113,521, and in Great Britain June 16, 1925.

This invention relates to machines for hackling flax, hemp, jute and analogous fibres. In machines of this class as usually constructed it is customary to grip the material to be hackled between suitable holders which are caused to rise and fall between revolving sheets to which are attached pins or combs which hackle or comb the material during its upward and downward movement. In this arrangement it is obvious that owing to the material rising and falling while the pins of the revolving sheets pass through it, various portions of the same holder full of material are subjected to different forms of treatment according to the speed the pins pass through the material, the said speed varying as the holders rise or fall or remain stationary. With a view to overcoming this objection it has been proposed to vary the speeds of the hackle sheets during the upward and downward movements of the holders by a somewhat complicated arrangement of change gearing and cam actuated clutch mechanism.

According to this invention the rise and fall of the head, or gearing effecting same is utilized to control a differential motion whereby the revolving sheets are driven at such varying speeds that the speed at which the pins pass through the material remains constant or practically constant whether the material is rising, falling, or remaining in a stationary condition.

In the accompanying drawings:—

Figure 1 is an elevation of the lower part of a hackling machine provided with a differential motion in accordance with the present invention.

Fig. 2 is a horizontal section of the mechanism shown in Fig. 1.

Fig. 3 is a side elevation in diagram showing the improvement in its general environment.

A indicates a lever which is raised and lowered by a cam a and connected by a rod a^1 and chain or other flexible connection with a pulley 1 on a shaft 2 on which is fixed another pulley 3 to which is attached a flexible element 4 from one end of which is suspended the rising and falling head 5 carrying the flax holders 6, and from the other end of the flexible element 4 is suspended a weight 7, all of which parts operate in the well known manner. The lever A is mounted upon a shaft a^2 and rigidly connected with it is a toothed sector a^3 . Gear-

ing with the toothed sector a^3 is a toothed wheel a^4 which is rigidly fixed upon a sleeve forming part of a toothed wheel a^5 . The latter gears with a wheel a^6 which in turn gears with a wheel a^7 of the differential motion and rotates it in alternate directions to add speed to the hackling sheets 9 when the channel is falling and subtract speed when the channel is rising. The wheel a^7 carries two bevel wheels a^8 which gear with two bevel wheels a^9 at opposite sides of the wheels a^8 . One of the wheels a^9 is rigidly fixed to the shaft B which drives the hackle sheets and the other wheel is rotatably mounted on such shaft and carries a wheel b which is driven by a change wheel b^1 and bevel gearing b^2 from the main driving shaft C.

What I claim as my invention and desire to secure by Letters Patent in the United States is:—

1. In a hackling machine, mechanism for reciprocating the material and actuating hackling means to operate on the material, and including a differential motion device so controlled by the movement of said material and driving the hackling means as to produce a uniform hackling action without regard to the direction of movement of the material.

2. In a hackling machine, mechanism for reciprocating the material and actuating hackling means to operate on the material, and including a differential motion device controlled by the movement of said material and operable to drive the hackling means at substantially the same speed relatively to the material in the variations of movement of said material.

3. In a hackling machine, a reciprocating head, hackling means to operate on the material movable with said head, and mechanism for reciprocating said head and actuating said hackling means and including a differential motion device so controlled by the movement of said head and driving the hackling means as to produce a uniform hackling action without regard to the direction of movement of the material.

4. In a hackling machine, a reciprocating head, hackling means to operate on the material movable with said head, and mechanism for reciprocating said head and actuating said hackling means and including a differential motion device controlled by the movement of said head to drive the hackling

means at substantially the same speed relatively to said head in the variations of movement of said head.

5. In a hackling machine, a reciprocatory head, revolving hackling means to operate on the material movable with said head, and mechanism for reciprocating said head and revolving said hackling means and including a differential motion device so controlled by 10 the movement of said head and driving the hackling means as to produce a uniform hackling action without regard to the direction of movement of the material.

6. In a hackling machine, a reciprocatory head, hackling means to operate on the material movable with said head, and mechanism for reciprocating said head and actuating said hackling means and including a differential motion device controlled by the 20 movement of said head and operable to drive said hackling means at substantially the same speed relatively to said head in the variations in movement of said head while it is reciprocated.

25 7. In a hackling machine, a rising and falling head, hackling means to operate downwardly on the material movable with said head, and mechanism for reciprocating said head and actuating said hackling means 30 and including a differential motion device controlled by the movement of said head to

add speed to and subtract speed from the hackling means when the head is falling and rising, respectively.

8. In a hackling machine, a reciprocatory head, hackling means to operate on the material movable with said head; an oscillatory lever operable with the movement of the head, two bevel wheels, one driven by power and the other operably connected with said 40 hackling means, a rotatable member operably connected with said lever to be rotated in opposite directions by the oscillation of said lever, and a bevel wheel carried by said member and meshing with said two bevel 45 wheels.

9. In a hackling machine, mechanism for actuating hackling means including two bevel wheels, one of which is driven by power and the other of which is adapted to 50 drive the hackling means, a rotatable member, a bevel wheel carried by said member and meshing with said two bevel wheels, and means adapted to operate with a reciprocatory head carrying the material to be 55 actuated on by said hackling means and controlling said member to rotate it in opposite directions by the movement of the head in opposite directions.

In witness whereof I have signed this 60 specification.

THOMAS BARBOUR.
